REPLACEMENT CARRIER SYSTEM

Richard C. Curtis, East Orange, N. J., assignor to
Wired Radio, Inc., New York, N. Y., a corpora-
tion of Delaware

Application December 21, 1937, Serial No. 180,972

7 Claims. (Cl. 179—15)

This invention pertains in general to signaling systems and specifically relates to an arrangement for transmitting and receiving modulated high frequency carrier energy with the carrier frequency itself suppressed or eliminated.

The principal object of the invention comprises providing a system and method of suppressed carrier transmission for generating modulated carrier energy and transmitting the same with the carrier frequency itself suppressed, and then, at the receiver, generating an independent carrier for replacement purposes and detection at the reception point to reproduce the desired signal with accuracy and without noticeable distortion.

A further object of the invention consists in producing a system for transmitting a plurality of suppressed carrier program channels to a receiving point with means at the receiving point for accurately generating and replacing any one of several harmonically related carrier frequencies to reproduce a desired program.

Another object comprises providing a replacement carrier system having a receiver control frequency generating source for controlling an intermediate replacement carrier frequency source operable at selected frequencies to provide replacement carrier frequencies in the reception and reproduction of suppressed carrier program channels at selected frequencies.

These and other objects will be apparent from the following, reference being had to the accompanying drawings in which like reference numerals designate corresponding parts, and in which:

Fig. 1 is a schematic representation of one embodiment of a transmission and reception system of the replacement carrier type in accordance with the invention; and

Fig. 2 is a diagrammatic representation of the details of circuits employed in the reception system of the arrangement depicted in Fig. 1.

The invention contemplates generating a base frequency and developing a plurality of harmonics therefrom, these harmonics being utilized in conjunction with various program modulation frequencies, to produce a plurality of modulated high frequency side bands with the carrier frequencies suppressed. In accordance with the invention, these side bands of frequencies are transmitted to a reception system. The reception system comprises a control oscillator for generating a controlling frequency, nominally of a high order. This high order frequency is then utilized to interlock with a selectively operable

intermediate oscillator adapted to thereby selectively produce a multiplicity of replacement carrier frequencies which are utilized in a mixing and detecting system to reproduce selected signals of programs as transmitted by the various side bands of frequencies.

Referring to the drawings in detail, and particularly to Fig. 1, the transmitter in the present embodiment of the invention comprises a crystal controlled base frequency supply source 1, which may be a crystal controlled electronic oscillator, or the like, for supplying a standard base frequency, such as 10 kilocycles. The output of the base frequency source 1 is directed to a harmonic generator 2 which generates harmonics of the base frequency. In the present embodiment, these harmonics are delivered to modulators 3, 4, 5, as frequencies of 30, 50, and 60 kilocycles, respectively.

Sources of modulation frequencies 8, 9, 10 provide various modulation frequencies to the modulators 3-5, individual to three program channels. The modulators 3-5 combine the respective carrier frequencies and modulation frequencies to produce high frequency energy in the form of modulation side bands with carriers substantially suppressed. Filters 13, 14, 15 restrict the output of the modulators 3-5 after passing through intermediate amplifiers, so as to pass one side band of desired width and substantially suppress the other side band. The spacing and arrangement of transmitted side bands may be substantially similar to those depicted in my copending application Serial Number 180,971, filed concurrently herewith, Patent No. 2,188,499, issued January 30, 1940.

The outputs of filters 13-15 are directed through power amplifiers, not shown, and thence through a composite filter 23 and an integration network 24 to a transmission medium 25. The transmission medium 25 may be of various forms, as, for example, in wired radio broadcasting, it may be a power transmission network.

The composite filter network 23, and the integration network 24, cooperate to produce the 45 conjoint and integrated distribution of the various frequencies over the transmission medium. The detailed construction and operation of these circuits is disclosed in a copending application of Henry R. Butler, Serial No. 161,389, filed August 28, 1937, Patent No. 2,179,612 issued November 14, 1939.

The reception system includes a power supply 30 connected to the transmission medium 25 for supplying operating voltages over the diagram- 55

matically indicated network 31 so that the various electron-tube operated equipment of the receiver may function properly.

According to the invention, a crystal controlled oscillator 35 produces a constant wave of a high order frequency, such as 150 kilocycles, this being the reception control frequency which, by crystal control, is maintained substantially equal to the fifteenth harmonic of the 10 kilocycle base frequency which also is crystal controlled at source 1. A variation of a few cycles per second from the true harmonic relation will not produce noticeable distortion in the received program. Such distortion would be a change in pitch of the received tones or notes equal to the number of cycles that the replacement carrier differs from the original suppressed carrier and therefore is noticeable, if at all, only at very low audio frequencies. The output of oscillator 35 is fed to an intermediate oscillator 36. The oscillator 36 has adjustable parameters and is adapted to produce frequencies over the range of carrier frequencies employed at the transmitter. I have discovered that the oscillator 36 will interlock with the control frequency of oscillator 35 and be held constant thereby when oscillator 36 is adjusted to approximately a multiple of the base frequency. The frequency of oscillator 36 can thus be maintained stable and substantially equal to any desired one of the carrier frequencies suppressed at the transmitter, the possible difference therebetween being governed by the accuracy of the crystal controls of oscillators 1 and 35. The output of the oscillator 36, comprising a controlled replacement carrier thus substantially corresponding in frequency to any desired one of the carrier frequencies developed by the harmonic generator 2, is directed to a mixer 37. The mixer 37 includes capacitive coupling 38b to the transmission medium 25, and derives therefrom the signalling energy comprising the modulation side bands previously discussed. These modulation side bands are then selected by the mixer 37, fed to detector 38 and amplifier 39, and then to the utilization or load circuit for reproduction of a program.

Referring to Fig. 2, it will be seen that the oscillator 35 comprises a crystal 40 associated with an oscillator circuit including electron tube 41. The electron tube 41 is of a multi-electrode type such as the 6J7 and includes necessary circuit components to form a crystal controlled oscillating circuit adapted to produce a relatively high order control frequency. In the present embodiment of the invention, this control frequency is 150 kilocycles.

The intermediate oscillator 36 includes a multi-electrode tube 45 which, in the present embodiment, is of the 6L7 type. The circuits connected with the tube 45 include an input connection to the control electrode from the output suppressor electrode circuit of the oscillator 35. The intermediate control electrode of the tube 45 is included in an adjustable resonant circuit 46 coupled with an inductance in the anode circuit 47.

Coils 49 and 50 are provided, as shown, conductively connected with a fixed capacitance 51 and variable capacitor 52. In the present embodiment of the invention, I have found that the inductance 50 of a value of 16 mh. is satisfactory, while the capacitance 51 may be 280 mmf. A connection 53 from the coil 50 is directed to the mixer 37 which includes a broadly tuned cir-

cuit having parts 37a and 37c on the input and output sides of electron tube 37b. The electron tube 37b is of the multi-electrode type, a 6L7 being here employed. The circuits 37a and 37c include variable capacitors, all of which are operated in unison for producing a broad tuning effect for selection of frequency bands transmitted over the lines 25. The output of mixer 37 is directed to a substantially linear detector 38 using a full wave tube 38a, type 6H6 being found satisfactory. The tube 38a provides for the sum and difference linear detection of the frequencies delivered thereto, its output circuit being directed to the amplifier 39.

The amplifier 39 includes an amplifier tube 39a and frequency cut-off circuit 39b. The tube 39a may be of the type 6C5. The circuit 39b is adapted to pass a definite range of audio frequencies and have a cut-off at a predetermined upper limit, for example, at 9 kilocycles. The cooperative function of the mixer 37, detector 38 and amplifier 39, including circuit 39b, with respect to the selection and detection of the frequencies, may be substantially the same as set forth in my above-mentioned Patent No. 2,188,499.

From the foregoing it will be seen that I have provided an arrangement for independently generating substantially synchronized equal carrier frequencies at transmission and reception points, the transmission carrier being signal modulated and transmitted with the carrier frequency suppressed, to the reception point where the transmitted and reception energies are combined for signal detection purposes.

Although a preferred embodiment of the system has been set forth, it will be understood that various modifications and changes can be made by those skilled in the art, but which will not depart from the intended scope of the invention. Therefore, no limitation is intended except as pointed out in the appended claims.

What is claimed as new and original to be secured by Letters Patent of the United States is:

1. A replacement carrier system for a series of carrier-suppressed side bands the respective carrier frequencies of which are harmonics of a constant base frequency at the transmission point, said system comprising at a receiving point, a local source of master control frequency, means independent of the transmitter for maintaining said control frequency constant at substantially an integral multiple of said base frequency whereby each said carrier frequency has a plurality of factors in common with said control frequency, a local oscillator selectively tunable to the frequencies of said carriers, and means including said control frequency source for maintaining the frequency of said oscillator constant and substantially equal to any one of said carrier frequencies when the oscillator is tuned thereto.

2. A replacement carrier system as defined by claim 1 in which the source of master control frequency comprises a plural-grid electron tube and a crystal having a natural frequency of vibration which is substantially a high-order harmonic of the base frequency, said crystal being connected between two grids of said tube.

3. A replacement carrier system as defined by claim 1 in which the source of master control frequency and the selectively tunable oscillator each comprises a plural-grid electron tube, a crystal connected between two grids of the source

tube, and a conductive connection from one said grid to a control grid of the oscillator tube.

4. In the art of signalling by transmitting only side bands of suppressed carriers which are harmonically related to a constant base frequency, the method for selectively replacing carriers on such side bands which comprises, generating at a receiving point a constant control frequency substantially equal in cycles per second to a high 10 order harmonic of said base frequency, generating oscillations having approximately the frequency of a selected one of said suppressed carriers, and stabilizing the frequency of said oscillations by said constant control frequency so that 15 the oscillation frequency is also constant and bears substantially the same harmonic relation to the base frequency as the frequency of the selected carrier.

5. In the art of signalling by single side bands 20 having their carriers suppressed, said carriers being low order harmonics of a constant base frequency at the transmitter, the method for replacing carriers at a receiving point which comprises, generating a control frequency at said receiving 25 point and keeping it constant at substantially a high multiple of said base frequency, generating a replacement carrier approximately equal in frequency to a desired one of the suppressed carriers, and controlling the exact frequency of the 30 replacement carrier and keeping it constant by said control frequency so that the replacement carrier is maintained at substantially the same frequency as the desired suppressed carrier.

6. In a receiver for suppressed-carrier side 35 bands the carrier frequencies of which are suit-

able for transmission over wires and are harmonically related to a constant base frequency at the transmitter, the method for providing replacement carriers which comprises, selectively generating at a receiving point sustained oscillations approximately equal in frequency to a desired one of the suppressed carriers, generating a frequency higher than all said carrier frequencies, maintaining said high frequency constant at substantially a multiple of said constant 10 base frequency, and stabilizing said selectively generated oscillations by said high frequency whereby the oscillation frequency is maintained constant at substantially the selected lower multiple of the base frequency corresponding to the 15 desired carrier.

7. In a receiving system for a group of carrier-suppressed side bands the carrier frequencies of which are harmonically related to a constant base frequency, a source of replacement carriers 20 comprising, a plural-grid electron tube, a crystal connected between two grids of said tube, means for biasing one said grid positive and the other grid negative with respect to the tube cathode, said crystal having a constant frequency of 25 vibration which is substantially a high order harmonic of said base frequency, an electron tube oscillator having a control grid and a circuit tunable to the carrier frequencies of the received side bands, and a conductive connection from 30 said negative grid of the crystal-controlled tube to the control grid of the oscillator tube for maintaining the oscillator frequency constant at any selected one of said carrier frequencies.
